UNITED STATES PATENT OFFICE.

HUBERT OSWALD BEDGOOD, OF GLASGOW, SCOTLAND, ASSIGNOR TO LOBNITZ & COMPANY LIMITED, OF RENFREW, SCOTLAND.

DIRECTLY-DRIVEN SLEWING GEAR FOR DRAG-LINE EXCAVATORS.

Application filed July 10, 1924. Serial No. 725,252.

To all whom it may concern:

Be it known that I, HUBERT OSWALD BEDGOOD, of Beechmount, 14 Dalkeith Avenue, Dumbreck, Glasgow, Scotland; a subject of the King of Great Britain, have invented certain new and useful Improved Directly-Driven Slewing Gears for Drag-Line Excavators, of which the following is a specification.

10 This invention relates to drag line excavators and has for its object to provide improved slewing gear for such machines.

Drag line excavators, as at present constructed, are usually provided with slewing gear comprising a fixed circular rack and a pinion wheel, which latter is driven through gearing by an engine on the turntable.

According to this invention the slewing of the excavator jib is effected by a direct drive from the slewing engine to the pinion without using intermediate gearing of any kind, whereby the construction and action of the slewing gear is considerably simplified.

25 It is also an object of the present invention to provide simplified mechanism so that the slewing operation can be controlled by the manipulation of a single hand lever.

One embodiment of the invention will 30 now be described by way of example and with reference to the accompanying drawings.

On the drawings:—

Fig. 1 is a side view of the slewing gear 35 partly in section along the line 1—1 of Fig. 2. The reversing gear and shaft bearings are in section while the turntable 4 of the machine is in outline.

Fig. 2 is a plan view of the gear and engine.

Fig. 3 is an enlarged detail view of the reversing gear.

The drag line A, its fairlead B and part 45 of the jib C are indicated to show the relative positions of the parts.

Referring now to the accompanying drawings, the numeral 1 denotes the stationary under-frame of the drag line excavator whereon is mounted the circular rack 2 with vertical teeth 3 on its inner wall. Concentric with and above the said rack there is

pivoted the usual revolving frame or turntable 4 which carries the jib C. 7 is the slewing pinion which gears with the rack.

The engine has two cylinders 5, 5, arranged at an angle, say, 90°. The single vertical driving shaft 6 has the slewing pinion 7 at its lower end and passes through the revolving frame or turntable 4 at the point of intersection of the axes of the cylinders 5, 5. Bearings 8 are provided for the shaft 6 in the ends of rods 9 secured to the cylinder housings, the said rods also serving as guides for the piston crossheads 10. The connecting rods 11, 11 are adapted to take on to a common crank 12 formed on the vertical driving shaft 6. With cylinders disposed as described only one eccentric sheave 13 is required to operate the valve gears of the cylinders, the eccentric strap 14 of the said 70 eccentric being connected to two eccentric rods 15, one to each of the cylinders 5, 5.

Reversal of the engine is provided for by turning the aforesaid eccentric sheave 13 round the driving shaft 6 by sliding sleeve 75 and scroll gear shown clearly in Fig. 3. To this end, a helix 16 is cut for a certain length in the upper end of the shaft 6. A sleeve 17 surrounds this portion of the shaft 6 and engages with the helix therein formed. The eccentric sheave 13 has an extended sleeve 18 formed on its lower side, the said sleeve embracing the aforementioned sleeve 17. Registering keyways are cut in the two sleeves 17 and 18 and a key 19 is inserted in 80 such a way that the said sleeves can slide, but cannot rotate relatively to each other. The bushing of the upper guide rod 9 hereinbefore described is extended into a cup 20 in which the sleeve 18 works. The sleeve 17 has double flanges formed at its upper end to receive the prongs of a fork 21, which fork is connected to the reversing lever 22, fulcrumed at 22a and operated by a reversing engine 23. This lever 22 also controls 85 the steam slide-valve 24, through which steam is supplied to pipes 25, 25 and thence to the cylinders. The valve 24 is closed in the central position and open in the other two positions. The pipes 28 are the cylinder exhausts. Control of the reversing engine is effected by a system of rods and

levers 26 operated by a lever 27 from any convenient part of the revolving platform or turntable 4.

Supposing the parts to be at rest in the 5 central position, the operation of the reversing and slewing gear is as follows:—

Steam is admitted to the engine 23 and the fork 21 caused either to rise or fall according to the direction in which the jib of 10 the excavator has to be moved. Fork 21 causes axial displacement of the sleeve 17 which, in virtue of its engagement with the helix 16, rotates. In turning, the said sleeve 17 also rotates the surrounding sleeve 18 of 15 the eccentric, no axial motion of which occurs. Thus the eccentric sheave 13 is rotated to the position which moves the slide valves of the cylinders 5 to effect the rotation of the pinion 7 and consequently the 20 slewing motion in the direction required.

The helix 16, in this embodiment of the invention, is a left hand screw; therefore, while the shaft 6 is rotating, say, in a clockwise direction as seen in plan, the sliding 25 sleeve 17 will tend to work down the shaft. Consequently, a counter-balancing thrust will be required to be exerted by the engine 23 at the other end of the fork 21. The thrust will be downward and will require to 30 be maintained as long as the engine is running in that particular direction.

To reverse, either this counter-balancing thrust is diminished or a thrust exerted in the opposite direction, when reversal will 35 take place as hereinbefore described, a very small movement of the sleeve being sufficient therefor. Motion of the reversing lever 22 will produce a movement of the valve 24, which controls the steam supply.

To stop, the sleeve 17 is allowed, or caused, to move to the central position, the resulting movement of the lever 22 operating the valve 24 and moving it to its central position thereby shutting off steam.

The reversing engine used is preferably 45 of the known combined steam and hydraulic type frequently fitted for the reversal of heavy marine reciprocating engines, and comprises a steam cylinder below, a controlling oil cylinder above, and a piston rod common to both and having a piston in each cylinder. A valve admitting steam to the steam cylinder and a valve controlling the flow of oil in the oil cylinder are interconnected and are provided with a hunting gear to bring them back automatically to their closed positions after operation of the engine, the piston rod being held in any desired position.

In the present instance the piston rod is 60 connected to the reversing lever 23 so that the sliding sleeve 17 and sheave 13 can be maintained in any required position. The reversing engine, and consequently the

whole slewing gear, is operable by a single 65 lever 27 through rods and levers 26.

It will be apparent from the foregoing description that, according to this invention, a very simplified slewing gear is provided 70 for drag line excavators, wherein all intermediate gearing is dispensed with and the engine design improved in such a way that the whole slewing operation is controlled by the movements of one lever.

Having now fully described my invention 75 what I claim and desire to secure by Letters Patent is:—

1. A drag line excavator having, in combination, an underframe, a circular rack upon said underframe, a turntable mounted 80 for rotation on said underframe, a vertical shaft carried by the turntable and carrying on its lower end a pinion that gears with the rack, a slewing engine which drives the said shaft directly, and a scroll gear on the 85 said shaft which causes the engine to stop, go ahead or reverse.

2. A drag line excavator having, in combination, an underframe, a circular rack upon said underframe, a turntable mounted 90 for rotation on said underframe, a vertical shaft carried by the turntable and carrying on its lower end a pinion that gears with the rack and a slewing engine having two cylinders arranged at an angle to one another and which conjointly drive the said shaft directly.

3. A drag line excavator having, in combination, an underframe, a circular rack upon said underframe, a turntable mounted 100 for rotation on said underframe, a vertical crankshaft carried by the turntable and carrying on its lower end a pinion that gears with the rack, a slewing engine having angularly disposed horizontal cylinders driving a single crank on the vertical crankshaft, and reversing gear comprising an eccentric rod for each cylinder, a single eccentric sheave to which the eccentric rods are connected, a scroll gear connecting said 110 sheave to said crankshaft whereby the position of said sheave relatively to the crank may be changed to cause the engine to stop, go ahead, or reverse, and means to alter the position of the scroll gear.

4. A drag line excavator having, in combination, an underframe, a circular rack upon said underframe, a turntable mounted 115 for rotation on said underframe, a vertical crankshaft carried by the turntable and carrying on its lower end a pinion that gears with the rack, a slewing engine having angularly disposed horizontal cylinders driving a single crank on the vertical crankshaft, a valve controlling the steam supply to the cylinders and adapted to close in central position, and reversing gear comprising an eccentric rod for each cylinder, a 120

single eccentric sheave to which the eccentric rods are connected, a scroll gear connecting said sheave to said crankshaft whereby the position of said sheave relatively to the crank may be changed to cause the engine to stop, go ahead, or reverse, a lever connected to the scroll gear to alter its position, and a connection from the said lever to the steam valve whereby the valve and the scroll gear are altered simultaneously.

5. A drag line excavator having, in combination, an underframe, a circular rack upon said underframe, a turntable mounted 15 for rotation on said underframe, a vertical crankshaft carried by the turntable and carrying on its lower end a pinion that gears with said rack, a slewing engine hav-

ing two horizontal cylinders disposed at 90° to one another and both driving a single 20 crank on the vertical crankshaft, a single valve controlling the steam supply to both cylinders, and reversing gear comprising an eccentric rod for each cylinder, a single eccentric sheave to which both eccentric 25 rods are connected, means whereby the position of the sheave relatively to the crank may be changed to cause the engine to go ahead or reverse, a lever to operate the said means, and a connection between the said lever and the steam valve whereby the said valve and the said reversing gear are operated simultaneously by the one lever.

In testimony whereof I affix my signature.

HUBERT OSWALD BEDGOOD.
